UNITED STATES PATENT OFFICE

125,793

DESIGN FOR A CHAIR

Willard H. Bond, Jr., East Grand Rapids, Mich.,
assignor to American Seating Company, Grand Rapids, Mich., a corporation of New Jersey

Application July 27, 1939, Serial No. 86,268

Term of patent 14 years

To all whom it may concern:

Be it known that I, Willard H. Bond, Jr., a citizen of the United States, residing at East Grand Rapids, in the county of Kent and State of Michigan, have invented a new, original, and ornamental Design for a Chair, of which the following is a specification, reference being had to the accompanying drawing, forming a part thereof, in which:

Figure 1 is a side elevational view of a chair, with a portion of the back broken away for convenience of illustration, showing my new design;

The characteristic features of my design reside in the portions shown in solid lines in the drawing.

I claim:

The ornamental design for a chair, as shown and described.

WILLARD H. BOND, JR.
